JAMES L. PATTERSON, OF FREEPORT, ILLINOIS, ASSIGNOR OF ONE-HALF TO JAMES F. PATTERSON, OF LEAF RIVER, ILLINOIS.

NUT-LOCK.

1,134,408.

Specification of Letters Patent.

Patented Apr. 6, 1915.

Application filed December 10, 1914. Serial No. 876,519.

To all whom it may concern:

Be it known that I, JAMES L. PATTERSON, a citizen of the United States, residing at Freeport, in the county of Stephenson and State of Illinois, have invented certain new and useful Improvements in Nut-Locks, of which the following is a specification.

This invention relates to nut-locks and has reference more particularly to that type of such devices which employ a U-shaped member, the arms of which are adapted to be received into slots formed in the threaded faces of the coöperating threaded elements for preventing the same from being relatively rotatably moved.

One of the primary objects of my invention is to provide in a nut-locking device of the above character novel means for preventing the U-shaped locking-member from being displaced from its operative position, whereby positive locking of the threaded members against relative rotary movement will be insured.

Another object of my invention is the provision of simple and effective means for locking a nut from rotary movement on a bolt, and such as may be cheaply and economically manufactured.

A further object is to provide in a nut-locking device of the above described character a construction wherein the threaded end of the bolt is shaped in a novel manner to provide for precluding the U-shaped locking-member from being removed and to permit said member to be easily removed at will by the use of a suitable tool.

Referring to the drawings: Figure 1 is a view in elevation of a nut-locking device embodying my invention; Fig. 2 is a longitudinal view taken on the line 2—2 of Fig. 1; Fig. 3 is a plan view of the locking device; Fig. 4 is a view in perspective of the nut-locking means in operative position as shown in Fig. 1; Fig. 5 is a view in elevation of my invention embodied in another form; and Fig. 6 is a plan view of the modification.

From an inspection of the drawings, referring more particularly to Figs. 1, 2, and 3, it will be noted that the bolt and nut designated generally by the reference characters 7 and 8 respectively, are of standard type with the exception of the formation of the threaded end of the bolt, which will be described hereinafter. The threaded face

of the bolt is formed with longitudinally extending slots 9 diametrically oppositely disposed, and the nut is formed on its threaded face with several pairs of diametrically oppositely disposed slots 11, each pair being adapted to register, or to be moved into alinement, with the slots in the bolt.

A U-shaped member designated by the reference character 12 formed preferably of a strip of resilient wire, as is clearly shown in Fig. 2 serves as means adapted to co-operate with the bolt and nut members to hold the same from relative rotary movement. The arm portions of the member 12 may be entered in the alined slots and the said member moved toward the bolt until substantially the full length of its arm portions have been moved into the slots to operative position. The function of the U-shaped member is readily apparent, since by the reception of the arm portions thereof in the alined slots the nut is precluded from turning on the bolt. To insure that this nut-locking means may not be withdrawn, I have provided a novel means for holding the U-shaped member in operative position, which means will now be described.

The threaded end of the bolt is formed with a reduced head 13 which is shaped to provide a cam-face designated by the reference character 14. The cam-face extends from a point in proximity to a plane passing longitudinally through the alined slots, away from the bolt at an angle to said plane and is arranged in the path of the cross-portion of the U-shaped member 12. When said member 12 is being moved to operative position said cross-portion will engage the cam-face and be sprung laterally with respect to said plane. At the inner end of the cam-face the head 13 is formed with a recess 15 into which the cross-portion of the member 12 will spring as said member is moved to its operative position. This movement of the said cross-portion is obvious since the cross-portion merely returns to its normal plane from which it has been sprung by forcing it against the cam-face 14 during movement to operative position. To facilitate springing the cross-portion of the member 12 laterally I have flattened this portion as is shown clearly in Figs. 1 to 4, making the upper end of said member more resilient and susceptible to lateral

movement. After the said cross-portion of the member 12 has entered the recess 15 said member will be precluded from being retracted by reason of the cross-portion abutting the upper wall of said recess. From the foregoing it is apparent that the nut-locking member 12 is positively locked from being displaced.

10 The sides of the head 13 adjacent to the aligned slots are cut away forming shoulders 16. When it is desired to remove the locking-member 12 any suitable tool (not shown) having a pair of spaced pointed members may be utilized for the purpose by inserting 15 said members in the openings 17 beneath the cup portion of the member 12 and above the shoulders 16 and drawn upwardly and outwardly with respect to the recess 15 to remove said cup portion therefrom.

20 In Figs. 5 and 6 I have shown a modified form of my invention in which the bolt and nut elements 7' and 8' respectively, and the U-shaped member 12' are constructed similar to the like members above described with 25 the exception of the means for preventing the member 12' from being withdrawn from operative position. In this construction the bolt has a reduced head 18 formed by cutting away the sides of the bolt adjacent the aligned slots to form the shoulders 16'. The 30 head 18 is slotted longitudinally as at 19 to receive the cross-portion of the U-shaped member 12', and a cotter-pin 21 passing through an aperture in the end 18 extending crosswise of the slot 19 above the cross-portion of the member 12' prevents the said member from being withdrawn. It will be noted that this construction makes provision 35 for permitting a tool to be inserted under the ends of the cross-portion of the member 12 above the shoulder 16' for withdrawing the said member from the slots.

I claim:

45 1. A nut-lock comprising a bolt and a nut therefor, each having longitudinal slots diametrically oppositely disposed on its threaded face and being adapted to register, and a U-shaped member the arms of which are adapted to be received in said slots, the 50 end portions of the bolt at the sides thereof adjacent to said slots being cut away to form shoulders and a reduced body portion intermediate the shoulders, said reduced body portion being shaped to permit the 55 cross-portion of the U-shaped member to be disposed in proximity to said shoulders and provided with means located at the outer side of said cross-portion for precluding the same from being moved outwardly to withdraw its arms from the slots.

60 2. A nut-lock comprising a bolt and a nut therefor, each having longitudinal slots diametrically oppositely disposed on its threaded face and being adapted to register, and a 65 U-shaped member the arms of which are

adapted to be received in said slots, the end portion of the bolt being provided with a cam-face disposed in the path of said cross-member when the same is being moved toward the end of the bolt to operative position, the cam-face being shaped to spring said U-shaped member laterally with respect to said slots by the engagement of the cross-portion with the cam-face, the cam-face terminating at its inner end in a laterally extending recess in which the said cross-portion is adapted to locate and be prevented from moving outwardly.

3. A nut-lock comprising a bolt and a nut therefor, the threaded faces of the bolt and nut having diametrically oppositely disposed longitudinal slots adapted to register, a U-shaped member the arms of which are adapted to be received into said registered slots to prevent the nut from turning on the bolt, and means engageable by the cross-portion of the U-shaped member for springing the same laterally with respect to a plane passing through said slots, as the said member is moved longitudinally to operative position.

4. A nut-lock comprising a bolt and a nut therefor, the threaded faces of the bolt and nut having diametrically oppositely disposed longitudinal slots adapted to register, 95 a U-shaped member the arms of which are adapted to be received into said registered slots to prevent the nut from turning on the bolt, and a cam-face at the threaded end of the bolt inclined with respect to a plane 100 passing through said slots and being arranged in the path of the cross-portion of said U-shaped member when the same is moved to operative position whereby to spring said member laterally with respect to 105 said plane.

5. A nut-lock comprising a bolt having longitudinal slots diametrically oppositely disposed on its threaded face and having at its threaded end a cam-face extending from 110 a point in proximity to a plane passing longitudinally through said slots, away from the bolt at an angle to said plane, a nut formed on its threaded face with longitudinal slots adapted to register with those on 115 the bolt, and a U-shaped member the arms of which are adapted to be entered in said registered slots and be moved longitudinally therein to operative position, such movement of the U-shaped member bringing the cross-portion thereof into engagement with said cam-face whereby to move the cross-portion laterally with respect to 120 said plane, and means permitting said cross-portion to be retracted laterally and for precluding the cross-portion from being retracted longitudinally of the bolt.

6. A nut-lock comprising a bolt and a nut therefor, each having longitudinally extending slots diametrically oppositely dis-

posed on its threaded face adapted to register, a U-shaped member, the arms of which are adapted to enter said registered slots for locking the nut from turning on the bolt, 5 the threaded end of the bolt being cut away on one of its sides adjacent to one of its said slots thereby forming a reduced end on the bolt, said reduced end being shaped to permit the cross-portion of the U-shaped 10 member, when said member is moved longitudinally on the bolt to effect locking of the nut, to be moved past and disposed within the said end of the bolt, and said reduced end being provided with means at the outer side of said cross-portion for precluding removal of the U-shaped member from the slots, the said cut-away portion of the bolt affording access to the underside of the cross-portion of the U-shaped member for drawing said member from the slots. 15
